COMBINED BILLFOLD, COIN PURSE, AND CARDCASE

David B. Jeffery, West Bend, Wis., assignor to
Amity Leather Products Co., West Bend, Wis.,
a corporation of Wisconsin

Application March 18, 1950, Serial No. 8,607

Term of patent 14 years

(Cl. D87—3)

To all whom it may concern:

Be it known that I, David B. Jeffery, a citizen of the United States, residing at West Bend, in the county of Washington and State of Wisconsin, have invented a new, original, and ornamental Design for a Combined Billfold, Coin Purse, and Card Case, of which the following is a specification, reference being had to the accompanying drawing, forming a part thereof.

Fig. 1 is a perspective view of one side of a combined billfold, coin purse, and card case embodying my new design;

Fig. 2 is a perspective view of the same side illustrating the card case and billfold elements in open position;

Fig. 3 is a perspective view of the opposite side of the article from that shown in Fig. 1; and

Fig. 4 is a view similar to Fig. 3 with the coin purse element in open position.

I claim:

The ornamental design for a combined bill-

fold, coin purse and card case, substantially as shown.

DAVID B. JEFFERY.
